DESIGN FOR A LUBRICANT DISPENSING APPARATUS

Arthur Fuller Dean, Winnetka, Ill., assignor to Stewart-Warner Corporation, Chicago, Ill., a corporation of Virginia

Application April 20, 1939, Serial No. 84,432

Term of patent 7 years

To all whom it may concern:

Be it known that I, Arthur Fuller Dean, a citizen of the United States, residing at Winnetka, in the county of Cook and State of Illinois, have invented a new, original, and ornamental Design for a Lubricant Dispensing Apparatus, of which the following is a specification, reference being had to the accompanying drawings forming part thereof.

Figure 1 of the drawings is a front perspective view of the lubricant dispensing apparatus, showing my new design;

Figure 2 is a top plan view thereof;
Figure 3 is an end view of Figure 2 looking in the direction of the arrow 3 of Figure 2; and
Figure 4 is an end view of Figure 2 looking in the direction of the arrow 4 of Figure 2.

I claim:

The ornamental design for a lubricant dispensing apparatus, as shown.

ARTHUR FULLER DEAN.
